[57] CLAIM

The ornamental design for a side element of a shoe upper, as shown and described.

DESCRIPTION

FIG. 1 is a perspective view of a side element of a shoe upper showing my new design;

FIG. 2 is a side elevational view thereof;

FIG. 3 is a top plan view thereof; and,

FIG. 4 is a front elevational view thereof.

The broken lines showing the remainder of the shoe upper and the sole are for illustrative purposes only and form no part of the claimed design.
